UNITED STATES PATENT OFFICE

FRANK BOWERS AND NORMAN L. SNOW, OF DETROIT, MICHIGAN, ASSIGNORS TO DIAMOND POWER SPECIALTY CORPORATION, OF DETROIT, MICHIGAN, A CORPORATION OF MICHIGAN

BOILER CLEANER

Original application filed March 5, 1923, Serial No. 623,031. Divided and this application filed February 18, 1926. Serial No. 89,185.

This invention relates to boiler cleaners and refers particularly to boiler cleaners employing the discharge of steam or other cleaning fluid to dislodge soot deposits and other accumulations from the boiler tubes and other parts of the boiler to be cleaned.

One of the objects of the invention resides in providing means for positioning the blower element longitudinally with respect to a boiler tube, a connection being established between the element and boiler tube so that the discharge nozzles of the blower element will occupy the desired relation to the boiler tubes and boiler tube spaces. The invention also provides means whereby manual adjustment may be made to change as desired, or initially locate the blower element with respect to the boiler tubes.

Another object of the invention is to provide means accessible exteriorly of the boiler for accurately adjusting a blower pipe longitudinally to properly locate the nozzles thereof with relation to the boiler parts to be cleaned. In other instances the adjustment means is located in the boiler wall or in the boiler setting proper.

It is also a feature of the invention that provision is made for adjustment of the blower pipe longitudinally or for complete withdrawal of said pipe from the boiler without taking the latter out of service.

This application is a division of our copending application Serial Number 623,031, filed March 5, 1923.

35 In the drawings:

Figure 1 is a sectional view showing a blower element equipped with the adjusting means;

40 Figure 2 is a cross sectional view along 2-2 of Figure 1 showing the valve mechanism;

Figures 3 and 4 are cross sectional views of the adjustment means taken respectively upon lines 3-3 and 4-4 of Figure 1;

45 Figure 5 is a detail cross section on line 5-5 of Figure 1 showing a feature of the valve control;

Figure 6 is a sectional view similar to Figure 1 but showing the head in elevation and

showing a modified form of adjustment means for the blower unit;

Figure 7 is a view illustrating an alternative connection between one of the boiler tubes and the blower pipe;

Figure 8 is a view similar to Figure 1 showing an alternative construction;

Figure 9 is a cross section on line 9-9 of Figure 8.

In these views the reference character A designates a boiler wall and B a number of the boiler tubes. C is a rotative blower pipe mounted transversely of said tubes and passing through an opening C² in said wall, said pipe being provided with suitable discharge nozzles C'. Exteriorly of the wall A a chambered head D is mounted fast upon the pipe C, said head having its outer end closed and being formed with an inlet port D' for steam or some other cleaning fluid. For rotating the blower pipe a shaft E is connected to the head D to drive the same, said shaft having a squared extremity E' engaging in a corresponding socket in the closed end of said head. F designates a chain wheel for actuating the blower pipe, said wheel being screw threaded upon a reduced stud F' formed upon the outer end of the shaft E. G and G' designate a pair of complementary members forming a valve chamber into which the head D projects through a packed journal bearing G² in the member G', said parts G and G' being clamped in coacting relation by bolts H. Between the members G and G' there is clamped a plate I having a steam port I' in the form of a sector of said plate. The plate I divides the valve casing G, G' into chambers J and J', the latter being in constant communication with the blower pipe C through the port D' and the former having a fluid supply pipe K opening thereinto. Within the chamber J a disk shaped valve member L is mounted fast upon the shaft E in close proximity to the plate I, said member preferably being welded upon said shaft. The valve member L has a sector portion removed therefrom, the radial marginal edges of said portion being indicated at M. When the blower pipe C is rotatively actuated by

80 means of the chain wheel F and shaft E, the 100

valve member L rotating with the shaft E closes communication between the chambers J and J' except during the interval of registration with the port I' of the opening formed in said valve member between the edges M thereof. Thus the size of the angle between the edges M accurately predetermines the arc of rotation of the blower pipe during which steam is discharged from the nozzles of said pipe. A portion of the surface of the disk I marginal to the port I' is slightly raised, as indicated at N, to form a seat for the valve member L. Owing to the considerable extent of said seat and to the considerable area of the valve member under a fluid pressure urging said member to said seat, a large frictional resistance would oppose turning of the valve member unless disengaged from its seat preliminary to rotation. The screw threaded mounting of the chain wheel F upon the outer end of the shaft E is for the purpose of effecting the desired preliminary unseating of the valve member. Thus when the chain wheel 25 is actuated to the right, said wheel initially turns upon the stud F', thus feeding inwardly relative thereto and exerting pressure upon a thrust bearing O to shift the shaft E outwardly and the valve member L clear of its seat, as is indicated in full lines in Figure 1. O' is a yoke member rigidly projecting from the casing element G and forming a seat for the thrust bearing O. When the blowing operation is completed it is necessary to shift the shaft E inwardly to again permit the valve member to properly seat under pressure of the cleaning fluid. This inward actuation of said shaft is accomplished by a slight reverse (or counter-clockwise) actuation of the chain wheel F whereby said chain wheel is turned upon the stud F and thus fed outwardly to its normal position indicated in dash lines. To prevent participation of the shaft E in the reverse travel 40 of the chain wheel an ordinary ratchet disk P is mounted fast upon said shaft between the yoke O' and casing G. A pawl P' mounted upon said yoke, is engageable with the teeth of said ratchet wheel. Thus when the chain wheel is reversely actuated, the shaft E is locked by engagement of pawl P' while the chain wheel is shifted upon said shaft to permit the valve member to seat.

Describing now the provision for adjustment of the pipe C longitudinally to properly position the nozzles C' thereof, Q designates a sleeve projecting integrally from the member G' into the wall opening C² and surrounding the blower pipe C. Said sleeve has a threaded portion engaged by a collar R to which collar are clamped by nuts S² threadedly engageable at opposite sides of the collar R, the outer ends of two rods R' projecting into the boiler and clamped at their inner ends by similar nuts to a collar S projecting

rigidly and preferably integrally from a collar S' which is clamped upon one of the boiler tubes. The threaded portion of the rods R' pass through openings S³ formed through collar R, these openings being of greater diameter than the rod R' whereby upon adjustment of nuts S² the collar R and blower pipe C may be adjusted longitudinally relative to rods R' and the boiler tubes. In this manner as clearly disclosed in Figure 1, the collar R is longitudinally adjustable upon the rods R' and since said collar is rigidly connected to the casing G, G' and the blower pipe is longitudinally fixed with respect to said casing, it is evident that any adjustment of the collar R will correspondingly adjust the pipe C longitudinally, thus relatively locating the blower pipe nozzles as desired relative to the boiler tubes. It is a feature of the described adjustment means that the blower pipe can be removed without taking the boiler out of service, this being effected by simply unscrewing the valve casing G, G' from the collar R and then withdrawing the blower pipe.

In the modified construction shown in Figure 6, T and T' designate sections of the blower pipe connected within the wall opening U by a coupling T². U' designates a pair of collars embracing the pipe sections T and T' at opposite ends of the coupling T², and V is a pair of rods clamping said collars in the described relation to the coupling and connecting the collars to a collar V' within the boiler and formed preferably integral with a collar V² clamped upon one of the boiler tubes W. Nuts V⁵ are provided for adjusting the collars U' relative to the rods V while suitable spacers V⁶ may be provided if desired to aid in maintaining the collars U' in spaced relation to each other. Thus it is seen that the blower pipe is held in any desired position of longitudinal adjustment owing to engagement of the coupling T² between the collars U'.

In the further modification illustrated in Figure 7, the blower pipe X carries a positioning member or set collar X' between a pair of arms Y integrally upstanding from a positioning member or collar Z clamped upon one of the boiler tubes Z'. This construction requires the collar X' to be shifted upon the blower tube X to vary the longitudinal adjustment of the blower pipe within the boiler.

In the alternative form of the invention disclosed in Figures 8 and 9 the blower pipe C³, ported valve seat I², disk valve L² and stem E², the chain wheel F² all correspond to the first described form of the invention. In this modification, however, a radially projecting lug L³ is formed marginally upon the valve member L² and is adapted to limit rotation of the valve member by engagement in the respective limiting positions with pins L⁴ and

5 L^5 projecting from the member I^2 . Thus in either of said limiting positions (as respectively indicated in dash lines and dotted lines in Figure 9) the valve member L^2 closes the port I^3 , said port being opened during a portion of an angular movement predetermined by the location of the pins L^4 and L^5 . In this construction the chain wheel is secured fast upon the stem E^2 by a pin F^3 .

10 It is also a feature of the construction just described that the positioning rods R^3 which engage a bracket S^5 carried by one of the boiler tubes W^3 extend entirely through the wall A^3 so that the nuts R^4 which clamp said rods to the collar R^2 upon the sleeve Q^2 are accessible exteriorly of the wall.

15 It is a common feature of the several described alternative adjustment devices that the blower pipe with its fluid supply head is fixed with relation to the boiler tubes to be cleaned rather than through attachment of said head to the boiler wall as in the prior practice.

20 The terms rotatable or rotative, as employed in the specification and claims of this application signify revoluble through either a partial revolution or a plurality of revolutions.

25 What we claim as our invention is:—

30 1. In a boiler cleaner, the combination with a discharge pipe for a cleaning fluid passing through a boiler wall, of a boiler tube extending adjacent said wall transversely of said pipe, positioning members for said pipe respectively engaging said pipe and said boiler tube and adjustable connections between said positioning members whereby the longitudinal position of said pipe may be varied with respect to said boiler tube.

35 2. In a boiler cleaner, a discharge pipe for a cleaning fluid passing through a boiler wall, and an adjustable connection accessible exteriorly of said wall between said pipe and an element of the boiler, said boiler element being located in the interior of the said boiler.

40 3. In a boiler cleaner, a discharge pipe for a cleaning fluid passing through a boiler wall, a head exteriorly of said wall including a valve for controlling a fluid supply to said pipe, said head carrying a rigid sleeve surrounding said pipe and projecting into said wall, and positioning members anchored interiorly of the boiler and projecting outwardly within the wall and engaging said sleeve.

45 4. In a boiler cleaner, the combination with a discharge pipe for a cleaning fluid passing through a boiler wall, of a valve outside of said wall controlling said pipe, the casing of said valve having a sleeve extending into said wall surrounding said pipe, a collar upon said sleeve, a boiler tube within the boiler, a clamping member upon said boiler tube, and an adjustable connection between said clamping member and said collar.

5. In combination with a boiler having a plurality of boiler tubes, a cleaner therefor, including a blower pipe positioned to discharge a cleaning fluid among the said tubes, a member secured to the blower pipe, a second member, means for clamping said second member to one of said tubes, said second member having means normally preventing relative movement between the blower pipe and the said boiler tube in a direction transversely of said boiler tube, said means cooperating with said first member, and adjusting means for locating said first member selectively at points along a portion of said blower pipe.

70 6. In combination with a boiler having a plurality of boiler tubes, a boiler cleaner therefor, including a blower pipe provided with a nozzle for discharging cleaning fluid among the boiler tubes, adjustable means connecting the boiler cleaner with a boiler tube whereby the blower pipe may be positioned transversely of the boiler tubes so as to locate the said nozzle at a predetermined point with respect to the boiler tubes, and means for preventing movement of the blower pipe transversely of the boiler tubes after the desired adjustment has been made.

75 7. In combination with a boiler having a plurality of boiler tubes, a boiler cleaner therefor, including a blower pipe provided with a plurality of nozzles spaced longitudinally of the blower pipe for discharging cleaning fluid among the boiler tubes, adjustable means connecting the boiler cleaner with a boiler tube whereby the blower pipe may be positioned transversely of the boiler tubes so as to locate the said nozzles at predetermined points with respect to the boiler tubes, and means for preventing movement of the blower pipe transversely of the boiler tubes after the desired adjustment has been made.

80 8. In combination with a boiler having a plurality of boiler tubes, a boiler cleaner therefor, including a blower pipe provided with a nozzle for discharging cleaning fluid among the boiler tubes, and adjustable means cooperating with one of said boiler tubes and adapted to be fixed to said blower pipe for positioning the blower pipe transversely of the boiler tubes so as to locate the said nozzle at a predetermined point with respect to the said boiler tubes.

85 9. In a boiler cleaner, the combination with a blower pipe passing through a boiler wall, of adjustable positioning means for said pipe secured to an element of the boiler interiorly of the boiler setting and projecting into the boiler wall to a position accessible from the exterior of the boiler wall for adjusting said pipe.

90 10. In a boiler cleaner, the combination with a blower pipe passing through a boiler wall and positioned transversely of a plurality of boiler tubes, of means for fixing said blower pipe against movement trans-

- versely of said boiler tubes, said means including a member fixed to an element of the boiler interiorly of the boiler wall and projecting into the boiler wall to a position accessible from the exterior of the boiler wall.
- 5 11. In a boiler cleaner, a discharge pipe for a cleaning fluid passing through a boiler wall, a head positioned exteriorly of said wall for supplying cleaning fluid to said pipe, and positioning members anchored interiorly of the boiler and projecting outwardly within the wall for engagement with the said head.
- 10 12. In a boiler cleaner, a sectional discharge pipe for a cleaning fluid passing through a boiler wall, a coupling connecting the sections of said pipe, collars embracing said pipe sections on opposite sides of said coupling, and an adjustable connection between said collars and an element of the boiler, said boiler element being located in the interior of the said boiler.
- 15 13. In a boiler cleaner, a sectional discharge pipe for a cleaning fluid passing through a boiler wall, a coupling connecting the sections of said discharge pipe, collars on the said pipe sections on opposite sides of the said coupling, a boiler tube within the boiler, a clamping member upon said boiler tube, and an adjustable connection between said clamping member and said collars.
- 20 14. In a boiler cleaner, a discharge pipe for a cleaning fluid passing through a boiler wall, a collar adjustably mounted on said discharge pipe, and a member clamped to an element located in the interior of the boiler, said member having arms embracing the collar on said discharge pipe for the purpose described.
- 25 15. In a boiler cleaner, a discharge pipe for a cleaning fluid passing through a boiler wall, a collar on said discharge pipe and adjustable longitudinally thereof, a boiler tube within the boiler, and a member clamped upon said boiler tube and having a pair of arms embracing the said collar on the said discharge pipe.

In testimony whereof we affix our signatures.

FRANK BOWERS.
